PUSH BUTTON SWITCH UNIT FOR TELEPHONE SYSTEMS

George Bruce Kamp, Springfield, Pa., assignor, by mesne
assignments, to Itt Terryphone Corporation, Harrisburg,
Pa., a corporation of Delaware

Filed July 9, 1964, Ser. No. 80,781

Term of patent 14 years

(Cl. D26—14)

FIG. 1 is a left side, top and front perspective view of a push button switch unit for telephone systems showing my new design; and

FIG. 2 is a left side elevational view, partly in cross section, the right side being substantially a mirror image thereof. The rear, not shown, is a substantially flat, unornamented surface.

I claim:

The ornamental design for a push button switch unit for telephone systems, substantially as shown and described.
